BROACHING MACHINE.

1,406,022.

Specification of Letters Patent. Patented Feb. 7, 1922.

Application filed February 21, 1920. Serial No. 360,439.

To all whom it may concern:

Be it known that I, MATTEO E. INFIORATI, Jr., a citizen of the United States, residing at New London, in the county of New London and State of Connecticut, have invented new and useful Improvements in Broaching Machines, of which the following is a specification.

This invention relates to broaching machines.

Some of the objects of the invention are: to produce a more practical device of the character mentioned; to increase or maximize the working capacity of a machine of this character by making it more thoroughly efficient. With these and other objects in view the invention resides in the particular provision, arrangement and combination of parts described in the following specification and illustrated in the accompanying drawing in which:

Figure 1 is a top plan view of a machine embodying the present invention.

Figure 2 is a side elevation.

Figure 3 is a vertical longitudinal section view.

Figure 4 is a detail transverse sectional view taken on the line 4—4 of Figure 3, illustrating more clearly how the tool holder block is arranged for movement and also illustrates the parts of the clutch.

Figure 5 is a detail sectional view taken on the line 5—5 of Figure 4.

Figure 6 is a transverse detail sectional view taken on the line 6—6 of Figure 3, and illustrates the reversing gears.

Figure 7 is a detail sectional view taken on the line 7—7 of Figure 3, and illustrates the nut and its correlated gears for pulling the broaching tool in a working direction.

Figure 8 is a detached perspective view of the keyed bushing with which the reversing gears are correlated.

Figure 9 is a diagrammatic view illustrating the manner of operation of the belt shifting means which is also utilized for actuating the toothed clutch forming a part of the invention.

At the outset, it might be well to explain that in order to successfully carry out the different broaching operations, the broaching tool, essentially, should be moved at a predetermined speed in its "working direction" and which speed is a slow speed as

compared with the return speed. It is essential for obtaining the maximum working capacity of a machine of this character that, the return of the broach be made at the quickest, practical possible rate of speed. It has been sought to attain these desirable characteristics hitherto but the machines in present use are not altogether satisfactory and the present invention is designed to overcome known objections and to render a machine of the present character comparatively practical and more thoroughly efficient.

Referring now to the drawing, it will be seen, that the machine includes pedestals 10 and 11. The pedestal 11 embodies a gear case 12 which encloses gears supported by the pedestal 11, the function of which gears will be explained hereinafter. A frame 13 is supported by the pedestals 10 and 11 and this frame embodies guides 14—14. A threaded element or screw 15 is arranged upon the machine and is adapted to be pulled in one direction which is to be known as the "working direction" and this screw is adapted to be rotated to effect the longitudinal movement of the screw in an opposite direction to its "working direction" which is to be known as the "reverse direction." The screw 15 is arranged between a slidable block 16 and driven means 17 which is rendered active by driving means 18. The block 16 is provided with grooves 19 which receive the guides 14—14. The block 16 has slidably and adjustably mounted thereon, a tool holder 20. Adjustment of the tool holder 20 is effected by the use of an adjusting screw 21 supported by a bracket 22 secured to said block.

In order that the screw 15 may be held against rotation at a predetermined time there is provided a toothed clutch 30 which comprises co-acting clutch elements 31 and 32. The clutch element 31 is loosely mounted on the screw 15 and is held against longitudinal movement with respect to said screw. The clutch element 32 is splined on the screw 15 as shown at 33 in Figure 4 of the drawing and is arranged for longitudinal movement with respect to said screw for co-action with the element 31. A spring pressed yoke 34 is pivoted as at 35 and this yoke is correlated with the clutch element 32. The spring 36 which bears against the upper free end of

the yoke 34 has a normal tendency to force the clutch element 31 into engagement with the clutch element 32 and a pivoted cam lever 37 is employed to effect movement of 5 the yoke 34 against its spring to maintain the disengagement of the clutch element 32 with the other element 31. The cam lever 37 is connected to a slide 38 by a pin and slot connection 39, the slide operating in a guide 10 40 and having its free end provided with anti-friction rollers 41.

The driven means 17 for effecting the movement of the screw 15, its correlated block 16 and tool holder 20, comprises a nut 15 45 which is mounted for periodical rotation in the bearing 46 forming a part of the gear case 12. A gear 47 is keyed to the nut 45 and this gear as well as the nut 45 is held against longitudinal movement with respect 20 to the screw 15 by the nuts 48, a thrust anti-friction bearing 49 and the spacer 50, inasmuch as the reverse gear 51 fills the space between the spacer 50 and the bearing 52 of the case 12. The reverse gear 51 is keyed to 25 a bushing 53 which surrounds the screw 15 and which bushing is provided with keys 54 which are received by keyways 55 in the screw 15. The bushing 53 is rotatable in the bearing 52 clearly shown in Figure 3 of the 30 drawing.

The driving means 18 comprises a shaft 60 which is mounted for rotation in bearings 61 forming a part of the pedestal 11 and a bearing 62 forming a part of the bracket 63 secured to the pedestal. A pinion 64 is secured to the shaft 60 and meshes with the gear 47. A bushing 65 surrounds the shaft 60 and has keyed thereto a gear 66 which meshes with the reverse gear 51. A pulley 40 67 is keyed to the bushing 65 and the shaft 60 has arranged thereon a loose pulley 68 and fast pulley 69. These pulleys are driven by a belt 70 which is shifted by means to be presently described which also serves to cause 45 the functioning of the clutch means 30. This latter means consists of a rod 71 which is slidably mounted in bearings 72 and has a belt encircling member 73. The rod 71 is slid by the use of a pivoted lever 74 which 50 has pin and slot connection 75 with said rod. A rod 76 is pivoted to said lever 74 as at 77 and is pivoted as at 78 to a hand lever 79 pivoted as at 80 to the frame 13. The rod 76 is disposed between the rollers 41 carried 55 by the slide 38 and in moving the rod by the use of the hand lever 79 to shift the belt 70, the slide 38 is moved upwardly and downwardly, as the case may be as well.

In practice and assuming that the broaching tool is to be moved in a working direction for dressing or for cutting away holes that are already in a piece of material, the hand lever 79 is moved to the position A shown in Figure 9 of the drawing which will 60 65 cause the belt 70 to be shifted to the pulley

69 and causes the slide 38 to move downwardly by reason of the engagement of the rod 76 with the rollers 41. The downward movement of the slide 38 causes the cam lever 37 to move to a position which permits 70

the spring 36 to move the yoke 34 on its pivot thereby causing the clutch element 32 to move into co-acting relation with the clutch element 31. Inasmuch as the clutch element 32 is splined upon the screw 15, and furthermore, inasmuch as the clutch element 31 is held stationary, the screw 15 will be held against rotation. The pulley 69 being a fast pulley causes the shaft 60 to rotate and through the intervention of the pinion 80 64 and the gear 47, the nut 45 will be caused to rotate with the result that the screw 15 will be pulled in a working direction. The return of the tool holder and its tool to its initial position is to be accomplished with 85 maximum practical speed as compared with the speed at which these parts travel in a working direction which is effected by moving the gear 47 at approximately 196 revolutions per minute. The ratio of the "return speed" as compared with the "working speed" is 10 to 1. In other words, the reverse gear 51 rotates 1,960 revolutions per minute as compared with the number of revolutions of the gear 47 in the same period of 90 time. The use of the reverse gear 51 and its companion gear 66 tends to the practicability 95 of the machine. The return movement of the screw 15, in a reverse direction, is accomplished by moving the hand lever 79 to 100 the position B shown in Figure 9 of the drawing which causes the belt 70 to move into operative relation with the pulley 67, and this movement of the hand lever 79 causes the rod 76 to move the slide 38 upwardly, which results in the movement of 105 the cam lever 37 to a position which causes the yoke 34 to move on its pivot and by reason of its correlation with the clutch element 32 to cause the same to move out of coacting 110 relation with the other clutch element 31, thus permitting the screw 15 to rotate freely. Inasmuch as the pulley 67 is keyed to the bushing 53, and through the intervention of 115 the gears 51 and 66, the bushing 53 will be caused to rotate. Inasmuch as the bushing 53 is provided with keys which enter the keyways 55 in the screw 15, the screw will be caused to rotate and inasmuch as the nut is held immovable by the sheer weight of 120 the gear 47 and the weight behind it of correlated parts, the screw will be moved by threading action in a reverse direction at a comparatively increased rate of speed. The screw 15 is made to move through a tube 125 housing 81 which ensures the safety of workmen who have occasion to approach the machine.

While there has been shown the preferred embodiment of this invention, it is to be un- 130

derstood that changes, alterations and modifications within the scope of the appended claims may be resorted to when desired.

What is claimed as new is:—

- 5 1. A broaching machine including a tool holder, a screw connected to said tool holder, means for periodically pulling said screw bodily in one direction without rotating the same and means for periodically rotating 70 said screw to move the same bodily in a reverse direction, and means for rendering the first mentioned means operative and inoperative.
- 10 2. A broaching machine including a tool holder, a screw connected to said tool holder, means for periodically pulling said screw bodily in one direction without rotating the same and means for periodically rotating said screw to move the same bodily in a reverse direction, the said means including 75 intermittently operable gears, and means for rendering the first mentioned means operative and inoperative.
- 15 3. A broaching machine including a tool holder, a screw connected to the tool holder and movable in a rectilinear path, means for pulling said screw in one direction without rotating the same, means for moving it in a reverse direction by rotating it, and 80 means for rendering said first mentioned means operative and inoperative.
- 20 4. A broaching machine including a reciprocal tool holder, a screw connected to said tool holder, driven means for moving the screw in one direction without rotating the screw including a threaded member engageable with said screw, a gear secured to said member, a shaft, a pinion which meshes with said gear on said shaft, belt 85 driven fast and loose pulleys on said shaft and belt shifting means for setting in motion the fast or the loose pulley.
- 25 5. A broaching machine including a tool holder, a screw having grooves therein connected to said tool holder, a screw threaded member which coacts with said screw, a gear carried by said member, a rotatable bushing having keys which are engageable in the grooves in said screw, a gear keyed to said 90 bushing, a shaft, a pinion keyed to said shaft which meshes with said first gear, a second shaft, a pinion keyed to said second shaft which meshes with said second gear, belt driven fast and loose pulleys on said 95 first shaft, a belt driven fast pulley on said second shaft, and belt shifting means for setting said fast pulleys in motion.
- 30 6. A broaching machine including a tool holder, a screw connected to said tool holder, mechanism for moving the screw comprising a threaded member engageable with said screw, a gear secured to said member, a keyed bushing whose keys are disposed in grooves in said screw, a gear secured to 100 said bushing, a shaft, a pinion secured to 105 said bushing fast on said shaft which meshes with said first gear, a second shaft, a gear which meshes with said second gear on said second shaft, a fast pulley on said second shaft and belt shifting means for selectively setting either of the said pulleys in motion for the movement of said tool holder back and forth.
- 35 7. A broaching machine including a tool holder, a screw connected to said tool holder, mechanism for effecting the movement of said screw in a rectilinear path at a predetermined speed in a working direction without rotating the same by pulling the same, and for effecting the movement of 110 said screw in a reverse direction at a predetermined increased speed as compared with its speed when moving in the working direction, by rotating the screw.
- 40 8. A broaching machine including a 115 slideable tool holder, a screw connected to the tool holder, means for moving said screw in one direction in a rectilinear path without rotating the same, and means for moving said screw reversely in a rectilinear path by rotating the same, the said screw being moved at a particular speed in one direction and at an increased speed in an opposite direction.
- 45 9. In a broaching machine, a slideable 120 block having mounted thereon a tool holder, mechanism for moving said block which includes a screw and a nut, driving means, a clutch embodying co-acting members one of 125 said members being held against longitudinal movement on said screw, the other of said clutch members being splined on said screw, and means for effecting the movement of said splined clutch member into co-acting relation with the other of said clutch members for rendering active the driving means.
- 50 10. In a broaching machine, a slideable 130 block having mounted thereon a tool holder, mechanism for moving said block which includes a screw and a nut, driving means, a clutch embodying co-acting members one of said members being held against longitudinal movement on said screw, the other of said clutch members being spring actuated and splined on said screw, and means for effecting the movement of said 135 splined clutch member into coacting relation with the other of said clutch members and for rendering active the driving means.
- 55 11. In a broaching machine, a slideable 140 block having thereon a tool holder, a screw connected to said block, mechanism for moving said screw to and fro which includes a nut, a clutch embodying coacting members one of said members being held against longitudinal movement with respect to said screw by said block, the other clutch member being splined on said screw, means for effecting the movement of said splined clutch 145
- 60 65 70 75 80 85 90 95 100 105 110 115 120 125 130 135 140 145

member into co-acting relation with the other clutch member to prevent the rotation of said screw and for allowing the operation of the driving means.

5 12. In a broaching machine a block having thereon a tool holder, mechanism for moving said block to and fro, which includes a screw, a nut which co-acts with said screw, driving means, a clutch, and means for rendering the driving means and clutch active to rotate said nut and to hold said screw against rotation relative to said nut.

10 13. In a broaching machine a block having thereon a tool holder, mechanism for moving said block to and fro, which includes a screw, a nut which co-acts with said screw, driving means, a clutch carried by said block and means for rendering the driving means active and for actuating said 15 clutch.

14. In a broaching machine, a block embodying a tool holder, mechanism for moving said block which includes a screw, a nut which co-acts with said screw, driving means, 20 a clutch for holding said screw against rotation when moving the block in one direction and means for rendering said driving 25

means active to cause the rotation of said screw to effect the return movement of said block at a predetermined speed.

30

15. A broaching machine comprising a slideable block which carries a tool holder, means including a screw operable to move said block to and fro at variable speeds, driving means including a driving belt, belt 35 shifting means including a rod, a clutch carried by said block which comprises co-acting members, a spring pressed yoke correlated with one of said members, a pair of levers one of which embodies a cam engageable with said yoke, the cam lever being operatively connected to said rod.

40

16. Mechanism comprising guides, a block arranged for movement on said guides, a tool holder adjustably mounted on said block, a reciprocating screw connected to said block, a clutch arranged on said block and operative to hold said screw against rotation at predetermined times, and means for moving said screw.

45

50 In testimony whereof I have affixed my signature.

MATTEO E. INFIORATI, JR.
